UNITED STATES PATENT OFFICE

EDWARD C. MOLITOR, OF SAN JOSE, CALIFORNIA

TOWING BAR

Application filed July 9, 1928. Serial No. 291,180.

This invention relates particularly to a bar designed for the towing of automobiles by other vehicles when they are unable to proceed under their own power.

- 5 It is one object of the invention to provide a bar so constructed and arranged that it may be quickly and easily connected to the vehicle to be towed and as quickly and easily removed therefrom.
- 10 It is also an object of the invention to provide a bar that has perfect freedom of movement about a given pivotal point with a minimum number of pivotal connections.
- 15 It is also an object of the invention to provide a device of the character indicated in which a compensating movement is secured in certain of the pulling parts whereby the strains are automatically equalized during a turning movement of the vehicle.
- 20 It is still another object to provide a device of the character indicated that will be light in weight, economical to manufacture, strong, durable and highly efficient in its practical application.
- 25 In the drawing:

Figure 1 is a perspective illustration of the bar head with a portion of the bar body and cables being shown.

Figure 2 is a plan view of the device in operative position relative to a car part broken away.

Figure 3 is an enlarged transverse cross-section through the head of the bar.

Figure 4 is an enlarged section on line 35 4-4 of Figure 2.

Figure 5 is an enlarged section on line 5-5 of Figure 2.

Referring now more particularly to the drawing, I show at 1 a tubular body portion having a threaded nut revolvably mounted on one end as at 2.

At 3 I show an externally threaded tubular element adapted to engage the threaded nut 2 and pass into the body 1 as shown. The element 3 is provided with a plurality of spaced orifices as 4.

A rod 5 is shown with an eye 6 formed on one end thereof, the other end slidably engaging the element 3 and having an orifice as 7 formed therein so that a pin as 8^a may

be inserted through any given orifice in element 3 and orifice 7 to hold the parts 3 and 5 in fixed relation to each other and yet permit longitudinal adjustment thereof.

On the end of the body portion 1 remote from nut 2 are mounted oppositely directed and radially arranged pins as 8.

The head 9 is provided with rearwardly extending and parallel arms 10 having pivotal engagement with the pins 8 as shown. A passage 11 is formed through the center of the head in axial alignment with the body portion 1 when in a normal position, the two sides of the passage curving forwardly and outwardly as shown at 12 and 13.

At 14 and 15 are a pair of cables of equal length connected to the end of element 3 in body 1 as shown at 16 and 17 respectively and passing over the curved seats 12 and 13 and fitted with hooks as 18 and 19 on their free ends.

When the device is to be used the hooks 18 and 19 are hooked on to the forward ends of the front springs of the vehicle to be towed, or to any other suitable spaced parts that may be available, and the nut 2 is then rotated to move the element 3 outwardly until the cables 14 and 15 are placed under proper tension substantially as shown in Figure 2. The rod 5 may now be connected to the tow car and the towing operation proceeded with.

By means of this device the car being towed is under complete control at all times, yet the cables effectually prevent shocks and vibrations developed in the rear vehicle from passing to the tow bar and thence to the towing vehicle.

The pivotal and eccentric mounting of the head 9 on body portion 1 is of special importance. When the body part 1 is moved into angular relation to the draft line of the vehicle being towed it turns on the pivots 8 while the head 9 remains in its original position. In swinging into this angular position, however, the connections 16-17 pass through the arc 20 but the resulting pull on the cable 14 is compensated for by a release of the tension on the cable 15. The result of this construction is that as the rod is turned in either direction into an angular position

relative to the draft line the cables slide in opposite directions on seats 12 and 13 and unequal bending strains that would tend to rupture or seriously weaken the cables are entirely eliminated.

By using a pair of flexible elements such as cables 14 and 15 some resilience is obtained between the vehicle being towed and the structure 1, 3, 5 so that vibrations developed in the vehicle being towed are effectually absorbed before they have had an opportunity to reach the towing vehicle, and yet the vehicle being towed is always under complete control. These flexible elements also obviate the necessity of providing another set of pivots to permit a vertical movement of the tow bar since they function as pivotal elements themselves.

To release the device it is only necessary to rotate the nut 2 backwardly whereupon the cables 14-15 are loosened and the hooks 18-19 may be readily removed from the vehicle springs 21.

It is to be understood, of course, that while I have herein shown and described but one specific embodiment of the invention, changes in form, construction and method of assembly and application may be made within the scope of the appended claims.

I claim:

1. A device of the character described comprising, a bar adapted to be connected at one end to a towing vehicle, a head pivotally mounted on the other end thereof for angular movement relative to its longitudinal axis, a pair of flexible elements attached at one end to the bar and extending in opposite directions over the said head and provided with means for connecting to a vehicle to be towed.

2. A device of the character described comprising, a bar adapted to be connected at one end to a towing vehicle, a pair of flexible elements adjustably connected at one end to the bar and extending beyond the end of the bar remote from the towing vehicle and provided with vehicle engaging means, and a head pivotally mounted on the bar and provided with a central passage and oppositely directed curved seats to engage the said flexible elements.

3. A device of the character described comprising, a bar adapted to be connected at one end to a towing vehicle, a member mounted for longitudinal adjustment relative thereto, a head pivotally mounted on the other end of the bar and provided with oppositely directed seats, and flexible towing elements connected at one end to the adjustable member and passing over the said seats.

4. A device of the character described comprising, a bar adapted to be connected at one end to a towing vehicle, a member mounted for longitudinal adjustment thereon, a pair of flexible towing elements connected to the

adjustable element, and tension equalizing means inserted between the bar and the two flexible elements.

5. A device of the character described comprising, a bar adapted to be connected at one end to a vehicle, a pair of flexible elements mounted on the other end of the bar and means for connecting the same to a vehicle to be towed, and on opposite sides of the draft line of the vehicle, means for placing the flexible elements under tension when connected to a vehicle, and tension equalizing means inserted between the bar and flexible elements to maintain their given tension when the bar is swung in either direction toward the connections of the elements to the vehicle.

6. A device of the character described comprising, a bar adapted to be connected at one end to a towing vehicle, a head pivotally mounted on the other end of the bar and directed away from the first mentioned end, a pair of flexible towing elements connected to the bar between the head and the first mentioned end and passing in opposite directions over the head on the side opposite from their connection to the bar.

7. A device of the character described comprising, a bar adapted to be connected to a towing vehicle at one end, a head pivotally and eccentrically mounted on the other end of the bar and outwardly directed relative thereto, and a pair of flexible towing elements connected to the bar between the pivotal mounting and the first mentioned end and passing in opposite directions over the head on its outwardly directed portion.

EDWARD C. MOLITOR.
